UNITED STATES PATENT OFFICE.

WILLARD A. DAVIS, OF CRANSTON, RHODE ISLAND, ASSIGNOR TO S. & B. LEDERER CO., OF PROVIDENCE, RHODE ISLAND, A CORPORATION OF RHODE ISLAND.

CONNECTER FOR WRIST-WATCH STRAPS.

Application filed April 8, 1926. Serial No. 100,763.

- This invention relates to an extension attachment for a wrist watch strap adapted to be unfolded for the purpose of extending the operating length of the strap, and the object 5 of this invention is to provide in such a member a pair of plates or sections hinged together at one end to fold one upon the other, means being provided for releasably retaining the sections in folded position, and 10 means also being provided for retaining one end of the strap in different adjusted positions along the length of one of the sections whereby the working length of the strap may be adjusted to fit the wrist of the wearer.
- 15 A further object of the invention is the provision of a detachable member preferably of the snap fastener type for adjustably connecting one end of the strap to this extendible member.
- 20 With these and other objects in view, the invention consists of certain novel features of construction, as will be more fully described, and particularly pointed out in the appended claims.
- 25 In the accompanying drawings:
- Figure 1 is a side elevation showing my improved extension member as attached to a wrist watch strap and in folded position.
- Figure 2 shows the inner plate of the 30 foldable member.
- Figure 3 is a perspective view showing the inner plate of the foldable member detached.
- Figure 4 shows one end of the strap part 35 illustrating the snap fastener stud secured thereto.
- Figure 5 is a longitudinal sectional view through the two extendible members showing them as folded one upon the other and the strap parts connected thereto.
- 40 Figure 6 is a sectional view on line 6-6 of Figure 5, showing the frictional fingers for retaining the extendible members in folded position.
- Figure 7 is a perspective view showing the 45 extendible strap member in extended position to temporarily lengthen the strap sufficiently to enable it to be passed over the hand onto the arm of the wearer.
- 50 It is found in the wearing of wrist watches of advantage in many instances, to be able to temporarily lengthen the attaching bracelet or strap to such an extent as to permit it to be passed over the hand onto the arm of the 55 wearer and to as quickly fold the same back
- into operating position to secure the strap in place; and to accomplish this in a simple and effective way, I have provided a pair of plates which are hinged together at one end and which are adapted to be folded one upon 60 the other and be releasably retained in folded position. Also I have provided simple and effective means whereby one member of the wrist strap may be adjusted along the length of one of the plates to regulate the 65 operating length of the strap to fit wrists of different sizes; and the following is a detailed description of the present embodiment of my invention and showing one means by which this advantageous result 70 may be accomplished:
- With reference to the drawings, 10 designates the inner plate of my improved extendible member which is provided at one end with a pair of marginal ears 11 pierced 75 as at 12 and bent back to form hinge members. This inner plate is also provided at its opposite ends with a pair of spring fingers 13 preferably undercut slightly on their inner faces as at 14, see Figure 6, and this 80 plate is also provided at its end with rearwardly bent fingers 15 to serve as a guide through which one part of the strap slides. Also, this plate is provided with a series of stud receiving holes 16 spaced along its 85 length.
- A cooperating extension plate 17 is provided with a pair of joint studs 18 formed integral with one end thereof, which are adapted to enter the eyes 12 in the ears 11 90 of its plate to hinge the two plates together, the opposite end of this plate 17 being provided with a bail 19 to which the end 20 of this strap portion 21 is secured. This plate has its center portion 22 removed for the 95 purpose presently described.
- The strap portion 23 has one end looped as at 24 about the bail of the watch 25 and near its free end I have inserted a spring stud 26 of the snap fastener type so that 100 the end 27 of this strap may be passed between the guide arms 15 of the plate 10 and this stud snapped into any one of the holes 16 along the length of this plate to regulate the operating length of the strap to fit wrists 105 of different sizes.
- After the two strap members have been secured to their different extendible plates and their hinge portions connected together they may be folded one upon the other into 110

the position illustrated in Figure 5, and the snap plate 17 is snapped between the resilient fingers 13 to releasably retain these plates in folded position one upon the other.

5 The cut out portion 22 of the plate 17 serves to receive that portion of the stud 26 which extends through its hole 16 in the inner plate 10.

By my improved construction the extendible member for the wrist watch is very strong and durable yet is very inexpensive to construct and the two plates may be readily folded one upon the other and releasably retained in folded position. Also the working length of the strap may be readily adjusted by snapping the stud 26 into any one of the holes 16 along the plate 10 to cause the strap to fit the arm to which it is applied.

The foregoing description is directed solely toward the construction illustrated, but I desire it to be understood that I reserve the privilege of resorting to all the mechanical changes to which the device is susceptible, the invention being defined and limited only 25 by the terms of the appended claims.

I claim:

1. In a two-part wrist watch strap, a connector for said parts comprising a pair of connector plates hinged together at one end, 30 means for detachably retaining said plates together in folded position, a series of holes in one of said plates, a glove-type resilient snap for fastening stud in one strap part to snap into said holes to secure the strap in

the different adjusted position, and means for 35 securing the other strap part to the other of said plates.

2. In a two-part wrist watch strap, a connector for said parts comprising a pair of plates hinged together at one end, an integral strap receiving bail on the free end of one section, one of said strap parts connected thereto and a strap guide on the corresponding end of the opposite section through which the strap end of the other 40 strap part extends, and means for adjustably securing the last said strap end to the section in which it is guided comprising stud and socket snap fastening connections 45 respectively positioned on said strap and section.

3. In a wrist watch strap, an extendible member comprising a pair of plates, one having a pair of integral laterally-extending hinge studs and the other a pair of integral bent-up pierced ears receiving said studs by which the two plates are hinged together, a pair of integral frictional fingers extending from the sides of one plate to snap over the side edges of the other plate to 55 releasably secure them in folded position, means for securing one of the straps to one of the plates, and means for adjustably attaching one end of another strap to the other of said plates.

In testimony whereof I affix my signature.

WILLARD A. DAVIS.
